TIME PIECE DIALS

Pierre Huguenin, Bienne, and Marcel Fetterle, Neuchatel, Switzerland, assignors to Huguenin & Cie, Bienne, Switzerland, a corporation of Switzerland

Application May 28, 1953, Serial No. 358,086

Claims priority, application Switzerland February 5, 1953

8 Claims. (Cl. 41—35)

The object of the present invention is a time piece dial, and especially a watch dial. This dial is characterized by the fact that it is provided with at least one recess extending at least in the region neighboring its periphery, by the fact that this recess is provided with a filling of transparent material, and by the fact that a decoration is provided which is situated in the recess and is visible through the material of the said filling.

The fact that the decoration, situated in the recess or recesses provided, is visible through a transparent material imparts to this decoration the aspect of enamel and enhances its relief.

The accompanying drawing illustrates, by way of examples, twelve embodiments of the dial constituting the object of the invention.

Fig. 1 shows a diametral cross section of the first embodiment.

The Figs. 2 to 12 are views similar to that shown in Fig. 1 and relative to the other eleven embodiments.

Fig. 1 shows a watch dial comprising a metallic plate 10 one of the faces of which is provided with a central recess 11 extending as far as the peripheric region of the dial, whereas its opposite face is provided with feet 12 enabling the plate 10 to be fixed to the movement of the watch. A decoration 13 situated in the recess 11 is visible through a mass 14 of transparent material which fills the recess 11 of the plate 10. The plate 10, the decoration 13 and the filling 14 are provided in their centre with a hole 15 through which the axis of the hands of the watch may pass. Fitted hour signs 16 are fixed onto the filling 14 by means of studs 17 passing through this filling and fixed in the plate 10.

Referring to Fig. 2, the watch dial comprises a metallic plate 18 provided with a central recess 19 which extends as far as the peripheric region of the dial, and with feet 20 enabling it to be fixed to the watch movement. A decoration 21 situated in the recess 19 is visible through a filling 22 of transparent material. Fitted hour signs 23 sunk in the filling 22 and visible through the latter are fixed to the plate 18 by studs 24.

The dial illustrated in Fig. 3 is a variant of the dial shown in Fig. 2, variant in which the hour signs 25 are surrounded by the filling 26, so that their upper faces are not covered by the latter.

The dial illustrated in Fig. 4 comprises a metallic plate 27 provided with an annular recess 28 situated in the peripheric region of the dial and in which is situated a decoration 29 which is visible through a filling 30 of transparent material. The recess 28 is arranged outside the zone of the hour signs 31, which are in one piece with the plate 27, and surrounds this zone.

The dial according to Fig. 5 is a variant of the one according to Fig. 1, variant in which the metallic plate 32 is provided with an annular recess 33 situated in the peripheric region of the dial. A decoration 34 and a filling 35 of transparent material are situated in the recess

2

33. The hour signs 36 are situated in the ring formed by the recess 33 and are fixed onto the filling 35.

The dial according to Fig. 6 is a variant of the one according to Fig. 5, in which the hour signs 37 are surrounded by the filling 38 of transparent material and are sunk in the latter excepting for their upper faces.

The dial illustrated in Fig. 7 comprises a metallic plate 39, which is provided with a first recess 40, which is annular and situated in the peripheric region of the dial, and with a second recess 41 arranged in the central region of the dial. Decorations 42 and 43 are respectively situated in the recesses 40 and 41 as well as respective fillings 44 and 45 of transparent material which enable the decorations 42 and 43 to be seen. The second recess 41 extends to within close proximity of the hour signs 46 which are in one piece with the plate 39 and formed with the latter by stamping. The two recesses 40 and 41 are thus separated by an annular part of the dial carrying the hour signs.

20 The dial according to Fig. 8 is a variant of the dial according to Fig. 7 in which the hour signs 47, which are distinct from the metallic plate 48, are fitted to the latter in the annular zone separating the two recesses.

Fig. 9 illustrates a dial comprising a metallic plate 49 which is also provided with an annular recess 50 arranged in the peripheric region of the dial and with a recess 51 placed in the central region of the dial, and with a raised annular fillet 52 separating the two recesses. In each recess 50 and 51 are situated a decoration and a filling 30 of transparent material allowing the decoration to be seen. The fitted hour signs 53 are situated in the ring formed by the recess 50 and are fixed onto the filling arranged in this recess.

Fig. 10 illustrates an embodiment of the dial similar to that shown in Fig. 9, with a variant consisting of the hour signs 54 being surrounded by the filling of the peripheric recess and sunk in this filling excepting for their upper faces.

35 The dial according to Fig. 11 comprises a metallic plate 55 provided with a peripheric recess 56 and with a central recess 57, the two recesses being contiguous but of unequal depth. The fillings 58 and 59 of transparent material are not of the same thickness so that these two fillings offer a smooth exterior surface which is continuous from the one to the other. The fitted hour signs 60 are fixed onto the filling 58 in the zone of the peripheric recess 56.

The dial according to Fig. 12 differs from the one shown in Fig. 11 only in that the hour signs 61 are surrounded by the filling of the peripheric recess, their upper surfaces being slightly raised above the upper surface of the filling of this recess.

In all the examples described the decoration may either be applied directly onto the bottom of the recess, or may 55 be borne by a piece of sheet material applied to the bottom of the recess or may be engraved on the bottom of the recess.

What we claim is:

1. Time piece dial, having at least one recess extending 60 at least in the region neighboring its periphery, said recess being provided with a filling of transparent material, characterized by the fact that a decoration is situated on the bottom of the recess and is visible through the material of said filling and that it comprises relief hour signs which are directly in contact with the said filling and which, seen from the front side of the dial, are surrounded by the filling.

2. Dial according to claim 1, characterized by the fact 70 that the hour signs are disposed directly on the said filling.

3. Dial according to claim 1, characterized by the fact that the hour signs are covered by the said filling.

4. Dial according to claim 1, characterized by the fact that the hour signs are laterally in contact with the filling.

5. Dial according to claim 1, characterized by the fact that the recess extends in a ring in which the hour signs are situated.

6. Dial according to claim 1, characterized by the fact that it comprises, in addition to the said recess, which extends solely in its region adjacent to the periphery, a second recess also provided with a filling of transparent material and with a decoration situated inside it and visible through the said material, this second recess extending in the central region of the dial.

7. Dial according to claim 6, characterized by the fact

that it is provided with a raised annular fillet separating the two recesses.

8. Dial according to claim 6, characterized by the fact that the two recesses are contiguous but of unequal depth, 5 the thickness of the filling being different from the one and the other so that the two fillings offer a smooth exterior surface which is continuous from the one to the other.
